PONTUS OSTENBERG, OF LOS GATOS, CALIFORNIA.

IMPULSE-STARTER FOR MAGNETOS.

1,291,097.

Specification of Letters Patent. Patented Jan. 14, 1919.

Application filed October 25, 1917. Serial No. 198,503.

To all whom it may concern:

Be it known that I, PONTUS OSTENBERG, a citizen of the United States, and resident of Los Gatos, in the county of Santa Clara 5 and State of California, have invented certain new and useful Improvements in Impulse-Starters for Magnetos, of which the following is a specification.

My invention relates to impulse starters 10 or spark intensifiers for magnetos in which the intensifying or interrupting detents or pawls are thrown into or out of action automatically according to the speed of the armature and driving shafts in connection 15 with which it is used, a particular feature of said detents being that they always move inwardly toward the axis of said shafts when they move into an operative position.

One object of the present invention is to 20 produce an intensifier for magnetos which will successfully cause a succession of hot sparks or kick-off sparks in the engine cylinders when the engine is started, again automatically assuming an operative position as 25 the engine slows down to a stop. Another object is to produce an intensifier operated by the centrifugal force manifested by the revolving shafts and parts connected thereto, thereby simplifying the construction of 30 the device and rendering it economical to manufacture, easy of installation, and greatly reducing the number of wearing parts and consequently rendering the device more durable than those forms commonly used. An 35 other object is to produce a device of the character indicated in which the detents may be automatically actuated to an operative position by gravity or other means and centrifugally actuated to an inoperative position.

With these and other objects in view my invention consists in the new and novel construction, formation, provision, combination and relative arrangement of parts, members 45 and features, all as hereinafter described, shown in the drawings, and finally pointed out in the claims.

In the drawings:—

Figure 1 is a side elevation of my improved impulse starter in operative relation to a magneto, part of the magneto being in section and part being broken away.

Fig. 2 is a sectional view on line A—A of Fig. 1, part being broken away.

Fig. 3 is a side elevation of another em-

bodiment of my invention the magneto and its flange being in section.

Fig. 4 is a sectional view on line B—B of Fig. 3, part being broken away.

Fig. 5 is a side elevation of another embodiment of my invention the magneto and its flange being in section.

Fig. 6 is a sectional view on line C—C of Fig. 5.

Similar characters of reference refer to 65 similar parts throughout the several views.

At 1 is shown a portion of a magneto having a flange 2 to inclose the working parts of my device, the driven armature shaft being shown at 3 and a stop mounted 70 on said magneto adjacent shaft 3 being shown at 4. To armature shaft 3 is secured plate 5 carrying hub 6. The driving shaft 7 has a plate 8 carrying hub 9 secured thereto and positioned in substantially parallel 75 relation to plate 5. A spring 10 encompasses hubs 6 and 9 and has its two ends secured to plates 5 and 6 respectively. In the present instance plate 5 is of smaller circumference than plate 8 and is provided 80 with two diametrically opposite lugs 11 and 12 projecting from its perimeter and lying in the plane of plate 5. Plate 8 is also provided with two diametrically opposite lugs 85 as 13 and 14, but these lugs are substantially perpendicular to the plane of plate 8 and project inwardly from its outer edge and are normally held in engagement with lugs 11 and 12 on plate 5 by said spring 10. Lugs 13 and 14 project a distance beyond plate 90 5 for the purpose hereinafter set forth. At a point near the outer circumference of plate 5, and on the surface of plate 5 facing magneto 1, is a pivot 15 carrying a detent 16. Detent 16 is curved substantially as 95 shown and is provided with a head 17 forming an offset 18 adapted to engage a stop 4 when said head 17 drops inwardly. The tripping end 19 of detent 16 is so formed and proportioned as to lie in the path of travel 100 of lug 13 when head 17 drops inwardly.

In operation, when driving shaft 7 is revolved slowly armature shaft 3 and the parts connected thereto are also caused to slowly revolve through the medium of a spring 10. 105 This device is designed to operate with shafts 3 and 7 in a horizontal position, therefore when plate 5 is revolved so far that pivot 15 approaches and passes the highest point in its circuit the force of gravity causes 110

head 17 to fall downward so that offset 18 engages stop 4 and tripping end 19 is thrown outwardly into the path of travel of lug 13, as indicated in dotted lines at 20. When 5 detent 16 engages stop 4 as described the movement of plate 5 (to which it is attached) is arrested. The continued movement of shaft 7, with plate 8 and lugs 13 and 14, winds up spring 10 and carries lug 13 10 around in the direction indicated by the arrow until it engages tripping end 19 of detent 16 thereby disengaging head 17 from stop 4. When detent 16 is released the increased tension of spring 10 throws plate 5 15 and armature shaft 3 suddenly forward at high speed until lugs 11 and 12 again engage lugs 13 and 14, thereby causing the hot spark desired. When, however, the engine is started and shafts 3 and 7 and parts connected thereto are rapidly revolved the centrifugal force operates to throw head 17 of detent 16 outwardly with the result that the device is automatically rendered inoperative at all times when the said shafts are 20 revolving at high speed, but automatically becomes operative when the engine slows down to a stop and the centrifugal force acting upon it becomes negligible.

It is apparent of course that if it is desired to use the device in a vertical position a light spring as 21 may be secured to plate 5 in an operative position against detent 16 so that the same may be forced into an operative position whenever the centrifugal force diminishes sufficiently to permit spring 21 to act. Also additional stops may be used for multi-cylindered engines, as indicated at 4^a, operating in connection with a single detent.

40 In the embodiment shown in Figs. 3 and 4 the stop 4 is secured to the flange 2 of magneto 1, and armature shaft 3 carries an H shaped member 22. Between each pair of arms of member 22 is a detent 23 pivoted 45 as at 24 near shaft 3. To plate 8 are secured a long stop-peg 25 and, diametrically opposite to peg 25, a short tripping-peg 26, the latter having a beveled end as 27. When detents 23 are to be gravity actuated 50 to an operative position the device is positioned vertically as shown in Fig. 3. In operation member 22 is normally in contact with stopping-peg 25. As shaft 7 and parts connected thereto is revolved slowly detents 55 23 assume the position indicated in dotted lines at 28, consequently one of them comes in contact with stop 4 thereby arresting the movement of shaft 3 and parts connected thereto. As shaft 7 continues to revolve 60 it brings the beveled end 27 of peg 26 in contact with the detent 23 in position 28 and forces the same upwardly and out of engagement with stop 4, whereupon spring 10 throws member 22 suddenly forward until the same is stopped by stop-peg 25 which

has advanced through a distance equal to that traveled by tripping-peg 26. When the device is rotated at high speed the centrifugal force operates to maintain detents 23 in a substantially horizontal position, in 70 which position they are, of course, inoperative.

In the embodiment shown in Figs. 5 and 6 the device is shown in a vertical position but the parts are reversed with reference 75 to their position in Figs. 3 and 4. In this embodiment shaft 3 also carries an H shaped member 22 having detents 23 pivoted at 24 between its respective pairs of arms, the stop 4 being positioned on magneto 1 80 near shaft 3 as in Figs. 1 and 2, and detents 23 having beveled upper ends as 29. In this embodiment detents 23 normally hang in a vertical position so that one of them will engage stop 4 when the device 85 is operated slowly. Member 22 is held normally in contact with stop 30 by spring 10, stop-peg 30 being secured to plate 8. When shaft 3 and parts connected thereto are held inoperative by detent 23 in engagement 90 with stop 4 the continued revolution of shaft 7 and plate 8 causes short tripping-peg 31, attached to plate 8, to contact with beveled end 29 of detent 23 thereby forcing the said detent 23 out of engagement with 95 stop 4, whereupon shaft 3 and the parts connected thereto are thrown suddenly forward until stopped by stopping-peg 30 which has advanced through the same distance traveled by tripping-peg 31.

100 In Figs. 3 and 4 the parts are shown at the moment of engagement of member 22 with stop 4. In Figs. 5 and 6 the parts are shown at the moment when tripping-peg 3 is about to operate detent 23, stop-peg 30 having advanced a distance. The dotted lines at 32 indicating the normal position of member 22 with relation to stop-peg 30. In these latter figures a double detent and tripping-mechanism is shown. At 105 33 in Fig. 5 one detent is shown with an outwardly and downwardly projecting arm, indicating that the said detent may be so formed as to be more effectively operated by centrifugal force if so desired, the action of the centrifugal force operating to raise arm 33 and thereby assist in moving the lower end of the detent outwardly. In this embodiment, as in the others, when the members are rotated at high speed the centrifugal force operates to maintain the detents in an inoperative position, the same automatically dropping back into an operative position as the rotating parts slow down to a stop. It is also pointed out that one 110 feature common to all of the embodiments is that the detent always moves inwardly toward the axle of the shafts 3 and 7 to engage stop 4 and thereby becomes operative, and away from said axis to become inoper- 115 120 125 130

ative, the movement in each direction being entirely automatic.

I claim:

1. The combination with a driven member mounted on the armature shaft of a magneto and a driving member yieldingly connected thereto, of a stop positioned adjacent said members and a detent pivotally mounted on said first mentioned member 10 gravity actuated toward the axis of said members and into engagement with said stop when said members are slowly revolved and centrifugally actuated to an inoperative position when said members are rotated at 15 high speed.

2. The combination with a driven member mounted on the armature shaft of a magneto and a driving member yieldingly connected thereto, of a stop positioned adjacent 20 said members and a detent pivotally mounted on said first mentioned member, means for automatically moving said detent inwardly toward the axis of said members and into engagement with said stop 25 when said members are slowly revolved, and means for automatically maintaining said detent in an inoperative position when said members are rotated at high speed.

3. The combination with a driven member mounted on the armature shaft of a magneto and a driving member yieldingly connected thereto, of a stop positioned adjacent 30 said members and a detent pivotally mounted on said first mentioned member, means for automatically moving said detent inwardly toward the axis of said members and into engagement with said stop when said members are slowly revolved, and centrifugally operated 35 means for automatically maintaining said detent in an inoperative position when said members are rotated at high speed.

4. The combination with a driven member mounted on the armature shaft of a magneto and a driving member yieldingly connected thereto, of a stop positioned adjacent 45 said members, a detent pivotally mounted on said first mentioned member and provided with a stop engaging end and a tripping end, means for automatically moving said stop engaging end inwardly toward the axis of said members and into an operative position with relation to said stop when said members are slowly revolved, 50 means carried by said second mentioned member adapted to engage the tripping end of said detent at a predetermined interval thereby removing said detent from engagement with said stop, and means for automatically maintaining said detent in an inoperative position with relation to said stop when said members are rotated at high speed.

5. The combination with a driven member 60 mounted on the armature shaft of a magneto

and a driving member yieldingly connected thereto, of a stop positioned adjacent said members and detent pivotally mounted on said first mentioned member, means for automatically moving said detent inwardly 70 toward the axis of said members and into engagement with said stop when said members are slowly revolved, means for automatically removing said detent from engagement with said stop after a predetermined interval, and means for automatically maintaining said detent in an inoperative position when said members are rotated at high speed. 75

6. The combination with a driven member mounted on the armature shaft of a magneto and a driving member yieldingly connected thereto, of a stop positioned adjacent said members and a detent pivotally mounted on said first mentioned member, 80 means for automatically moving said detent inwardly toward the axis of said members and into engagement with said stop when said members are slowly revolved thereby arresting the movement of said first mentioned member, means carried by said second mentioned member for disengaging said detent from said stop after a predetermined interval, means for limiting the forward movement of said first mentioned 85 member with relation to said second mentioned member when said detent is disengaged from said stop, and centrifugally operated means for maintaining said detent in an inoperative position when said members are rotated at high speed. 90

7. The combination with a driven member mounted on the armature shaft of a magneto and having a driving member yieldingly connected thereto, of a stop 105 mounted on said magneto adjacent said members and said armature shaft, and a detent pivotally mounted on said first mentioned member and having a stop engaging head and a tripping end, said head being gravity actuated toward said armature shaft and into engagement with said stop when said members are slowly revolved, means carried by said second mentioned member for engaging said tripping end of 110 said detent when said members are slowly revolved thereby disengaging said head from said stop, and means for maintaining said detent in an inoperative position when said members are rotated at high speed. 115

8. The combination of a driven member mounted on the armature shaft of a magneto and having a lug projecting radially therefrom, a driving member yieldingly connected thereto and having a lug projecting 125 therefrom and normally engaging said first mentioned lug, a stop positioned adjacent said members and said shaft, a detent pivotally mounted on said first mentioned member, means for automatically moving said 130

detent inwardly toward said shaft and into engagement with said stop when said members are slowly revolved, means for disengaging said detent from said stop at pre-
5 determined intervals when said members are slowly revolved, and means for main-
taining said detent in an inoperative posi-

tion when said members are rotated at high speed.

In testimony whereof I have hereunto af-
fixed my signature this 18th day of October,
1917.
